SAFETY LATCH FOR BAR PINS, BROOCHES, AND THE LIKE

Filed Dec. 3, 1929.

FIG. 1

FIG. 2

FIG. 3

Inventor

Robert G. Finley

By Carl Miller

Attorney

UNITED STATES PATENT OFFICE

ROBERT GEORGE FINLEY, OF NORMAN, OKLAHOMA

SAFETY LATCH FOR BAR PINS, BROOCHES, AND THE LIKE

Application filed December 3, 1929. Serial No. 411,366.

This invention relates to a safety catch or snap for the pin of a brooch, breast pin or similar article of jewelry, the construction and operation of the same being hereinafter described, and the novel features thereof pointed out in the claim.

Reference is had to the accompanying drawing wherein:

Figure 1 is an elevational view of the brooch, with the safety catch open.

Figure 2 is a fragmentary elevational view with the safety catch closed, and

Figure 3 is an end view of the safety catch end with the safety catch closed.

15 Mounted adjacent one end of the body of the brooch 10 on the back 11 thereof, is a bifurcated standard 12 which is secured thereto in any suitable manner as for example solder or rivets, not shown. Between the 20 arms 13 of the standard 12 is pivotally mounted the pin 14 which has formed on one end thereof an eye 15 through which the pivot 16 extends, all of which is of conventional design.

25 Directly opposite the standard 12, and rigidly secured in any desired manner to the back 11 of the brooch 10, is a catch 17, comprising a leg 18 terminating at its upper end in a C-shaped portion 19, clearly shown in 30 Figure 3. As will be noted the pointed end 20 of the pin 14 is adapted to be freely slid or inserted into the C-shaped portion 19 which is preferably formed on the leg 18 at such a height as to be substantially in the 35 same plane with the pivot 16.

A latch 21 is rotatively mounted on the pivot pin 22, which is carried by the leg portion 18 of the catch 17 at a point adjacent the bottom of the C-shaped portion 19, and substantially in the mid portion of the catch 17. The latch 21 is of semi-circular form and has integrally formed therewith an arm 23, which is adapted to extend outwardly of the brooch 10, when in "open" position, as shown 45 in Figure 1.

When the catch 17 is open the parts are in the position shown in Figure 1, so that the end 20 of the pin 14 is adapted to be easily placed within the C-shaped portion 19. To 50 lock the catch, all that is necessary is to move

the latch 21 through an angle of 180°, whereby the semi-circular portion of the latch 21 will completely close the opening of the C-shaped portion 19, as clearly shown in Figure 2, thereby locking the pin 14 in place. The latch 21 is prevented from unlocking due to its abutting the material (not shown) to which the brooch is fastened.

While a preferred embodiment of safety catch for a brooch, etc., has been shown, the same is susceptible of various modifications within the scope of the appended claim.

Having thus described my invention, what I claim as new and desire to secure by Letters Patent is:

In an article of jewelry, a body, a standard rigidly secured to the rear of said body adjacent one end thereof, a pin having an eye at one end thereof pivotally mounted in said standard, a safety catch rigidly secured to the rear of said body and directly opposite said standard, said safety catch comprising a leg portion and an upper C-shaped portion, a pivot pin on said leg portion, a semi-circular latch rotatively mounted on said pivot pin, and an arm integrally formed with said latch and extending from said latch in a direction along the diameter thereof, said arm extending outwardly from said body when said catch is open.

In testimony whereof I affix my signature.

ROBT. GEORGE FINLEY.
